UNITED STATES PATENT OFFICE.

JOHN H. BARR, OF ITHACA, NEW YORK.

RIBBON-FEED MECHANISM.

Application filed May 9, 1927. Serial No. 189,890.

This invention relates to ribbon feed mechanisms for typewriters and similar printing devices, and has for its objects the production of a simple and positive mechanism by which the ribbon is fed at each printing stroke, together with a quick acting automatic ribbon reverse mechanism operating on a single stroke of a key, and simple means for rewinding and changing ribbons. Other objects are to avoid unnecessary friction and binding, to prevent accidental displacement of the mechanism by vibration or driving forces, to make a construction which is readily adapted to quantity production under modern manufacturing processes and in general to produce an efficient and convenient device of the class described. Various other objects will become apparent as the description proceeds.

20 In the drawings forming part of this specification;

Fig. 1 is a plan view of the ribbon shift mechanism in one position of operation.

Fig. 2 is a similar plan view showing the feed shifted to the reverse position of operation.

Fig. 3 is a detail of the spool device and return release.

Fig. 4 is a view in elevation of the ribbon feed showing the ribbon shift mechanism, and one ribbon spool assembly.

Fig. 5 is a detail in elevation of the yieldable detent bearing for the cross-shaft.

Fig. 6 is a detail view partly in cross-section on the line A—A of Fig. 5.

Fig. 7 is a detail plan view of a worm feed and cross-shaft bearing.

Fig. 8 is a plan view of the ribbon feed ratchet.

40 Fig. 9 is an elevation of the same in one position of operation.

Fig. 10 is a similar elevation in a second position of operation.

Similar reference numerals refer to the same parts throughout the various views.

Referring first to Fig. 1 and Fig. 2, the typewriter ribbon 1 is mounted to travel between two spools 2 and 2', on which it winds and unwinds as is usual in typewriters. Inasmuch as the present invention concerns improvements in the means for driving these spools 2 and 2', and for reversing the direction of travel when the end of the ribbon has

been reached, I will first describe the mechanism by which the spools are rotated, and then describe the means by which the direction of rotation of the spools is reversed when desired.

Referring now more especially to Fig. 4, the spool 2 is detachably mounted on the upper end of the shaft 3, so as to rotate therewith—the shaft 3 being journalled for rotation in the ears 4 and 5 of the supporting bracket 6. In order that the spool 2 and shaft 3 may not run too easily and overtravel, a compression spring 7 is mounted on the shaft 3 between the collar 8 and the bearing ear 4—this spring 7 creating enough frictional drag on the shaft 3 to keep the spools from unwinding too freely. The shaft 3 is driven thru a pair of cams or ratchets 3' which are carried on a hub secured to the lower end of the shaft 3, as shown for example in Fig. 3 and Fig. 4. These cams 3' have an inclined face and a perpendicular face, and when the shaft 3 is being driven the perpendicular face is engaged by one of the spokes of the worm wheel 9, forming a positive drive. As shown for example in Fig. 3, it is desirable that the number of spokes of the worm wheel 9 should differ from the number of cams or teeth 3', so as to reduce the angular travel necessary for engagement. Various combinations of numbers of spokes and numbers of teeth may of course be used. The worm wheel 9 is loosely mounted on the shaft 3, and free to slide vertically thereon until its hub strikes the lower side of the ear 5—the clearance being sufficient to permit the spokes of the worm wheel 9 to ride up over the tops of the inclined faces of the cams 3' if the spool shaft 3 is turned in the proper direction. This permits a rapid winding by turning the spool 2 by hand, when changing a ribbon, as will be described. The spring 7 serves to hold the shaft 3 down in place, so that there is always sufficient clearance for the worm wheel 9 to ride up. The worm wheel 9 is rotated by a worm 10, which is mounted on a worm shaft 11, as clearly shown in Fig. 1 and Fig. 7. The worm shaft 11 extends across to operate the other spool 2' in a somewhat similar manner when the direction of ribbon feed is reversed, as will be described (see Fig. 2).

The cross shaft 11, at about its middle point, (see Fig. 1) has a ratchet wheel 12 se-

cured thereto, which is operated by a pawl 13 shown in Fig. 4, and also more in detail in Fig. 8, Fig. 9, and Fig. 10. The ratchet wheel 12 is substantially in the middle of the shaft 11, so as to be adjacent the pivot 32, in order that oscillations of the shaft 11 about the pivot 32 will not seriously affect the relation of the ratchet 12 to the pawl 13—the ratchet merely shifting slightly sideways along the edge of the pawl tooth. The pawl 13 is yieldably attached to the link 14 by means of the pin 15 and spring 16, which holds the pawl 13 in contact with the ratchet 12, yet permits the pawl 13 to ride up on the return stroke, as shown for example in Fig. 10. The link 14 is pivotally connected by the pin 17 to the ears 18 which are secured to and form part of the bail 19. This bail 19 extends substantially across the machine and is pivoted at its ends in the bearings 20, about which it may swing when struck by a driving member, such as 21. Each of the printing keys of the typewriter is provided with a driving member 21 which is actuated whenever a printing key is pressed, so that whenever one of the keys is operated some one of the driving members 21 moves forward and strikes the bail 19. Any suitable key actuated driving element may be used, for example as shown in my copending application, Serial No. 26,850, filed April 30, 1925, for typewriter, and as the particular form of the key action does not concern the present invention, it need not be described in further detail here.

The swinging bail 19 has attached thereto a tension spring 22, which serves to retract it after it has received the impulse of the driving member 21. The operation is clearly shown in Fig. 4, Fig. 9 and Fig. 10. Starting from the position shown in Fig. 9, the key actuated driving element 21 moves forward, strikes the bail 19, and swings it about the pivot 20 down to the position shown in Fig. 10. The pawl 13 engaging the ratchet 12 rotates it in the direction of the arrow. Since the pivots 17 and 20 are approximately in the line of action at the start, a substantially harmonic motion results, that is, the initial linear motion of the pawl 13 is slow relative to the initial angular motion of the bail 19, but increases in speed as the motion progresses—thus driving the ratchet 12 without unnecessary shock. On the return motion, as the driving element 21 recedes, the spring 22 retracts the bail 19, and the pawl 13 rides up and back over the teeth of the ratchet 12. A rod 24 may extend to the ribbon vibrator, if desired, so that it may also be operated by the bail 19.

The rotation of the ratchet 12 as described is transmitted thru the shaft 11 to the worm 10 and worm wheel 9, which rotates the shaft 3 and spool 2 to feed the ribbon 1 along step by step as the keys of the typewriter are operated. It will be noted that by the construc-

tion described the ribbon is positively fed with each printing stroke but the ribbon is not moved when operating the space bar or in the traverse of the carriage by hand. This permits the ribbon to be used in a uniform and economical manner.

I will now describe the mechanism by which the direction of travel of the ribbon is automatically reversed, so that it may be alternately wound from one spool to the other, as long as desired, without attention on the part of the operator.

Referring more particularly to Fig. 1 and Fig. 2, in which the bail 19 is only shown diagrammatically, and the ratchet driving pawl described is omitted for the sake of clearness, the frame 30 which supports the bearings 31, 31' of the cross-shaft 11, is mounted on a fixed pivot at 32 so that it may swing to a certain extent—permitting either one worm 10 or the other worm 10' to be brought into contact with their respective worm wheels 9 or 9'. To induce this swing of the frame 30 at the proper time, a second frame 33 is mounted so that it may slide on the frame 30, and shift thereon longitudinally of the cross-shaft 11. This frame 33 has bearing ears 34 and 34' attached thereto, thru which pass the shaft 11—the shaft 11 being free to slide longitudinally therein as well as rotate.

Since the shaft 11 also passes thru the bearings 31, 31' of the frame 30, the frames 30 and 33 are thus connected together, with the frame 33 being slidable on the frame 30 in the direction of the shaft 11.

Two clips 35, 35', having hooks 36, 36' are slidably mounted on the cross-bar of the frame 33, being held against the stops 37, 37' by the springs 38 and 38' respectively. At two points the bail 19 is provided with projections 40 and 40', which are spaced apart somewhat differently from the hooks 36, 36'—so that the projections 40 or 40' can only engage one hook 36 or 36' at a time.

After the frame 33 has been shifted into the proper position, the hook 36 comes directly under the projection 40, and when the bail 19 is swung downward as has been described, the projection 40 strikes the hook 36 and swings the frames 30 and 33 around the pivot 32 so as to withdraw the worm 10 from engagement with the worm wheel 9, that is, moving it from the position shown in Fig. 1 to that shown in Fig. 2. At the same time the worm 10' is swung into engagement with the worm wheel 9'. Since the worms 10 and 10' have threads of opposite pitch, this serves to reverse the motion of the ribbon spools 2 and 2'. The line of pull of the worm shaft, being somewhat offset from the pivot 32, helps to hold the worm in engagement.

It may sometimes happen that when one of the hooks 36, 36' is in the process of being shifted under one of the projections 40, 40' it may press against the side of the projection

and create enough friction to prevent the bail 19 from being retracted by the spring 22. It is to obviate this possibility that the hooks 36, 36' are mounted on slideable clips retained 5 by yielding springs 38 and 38', instead of being rigidly secured to the cross bar of the frame 33. If by chance one of the hooks 36, 36' bears against the side of the projection on the bail 19 and threatens to stop it, the amount 10 of force the hook can bring to bear is limited by the spring 38 or 38', and this is proportioned so as to be insufficient to hold the bail 19 from returning.

Since only one impulse applied to the bail 15 19 is required to swing the frame 30 on the pivot 32, this shift operates on a single stroke of the typewriter key, after the frame 33 has been moved into the proper position relative to the projections on the bail 19. In order to 20 shift the frame 33 into the proper position, a pair of forked levers 42 and 42' are provided, engaging pins 43 and 43' on the frame 33. These levers 42 and 42' are pivoted at 44 and 44' respectively, and the other ends of the levers 25 extend up into the path of the ribbon 1, and are provided with slots 45 and 45' respectively thru which the ribbon passes. The ribbon 1 is provided with the usual clips 46 and 46' near each end, and when the ribbon is 30 substantially unwound from a spool, such as 2 in Fig. 1, the clip 46, being too large to pass thru the slot 45, carries the lever 42 along with the motion of the ribbon, and shifts the frame 33 in the direction of the spool 2. This brings 35 the hook 36' under the projection 40', so that when the bail 19 is swung down by the next stroke of a typewriter key, the worm 10' is swung out of mesh and the worm 10 is thrown into mesh, as shown in Fig. 1. Figs. 1 and 2 40 show the position after the automatic shift has been effected. The spool 2 then starts to wind up the ribbon again. When the other end of the ribbon is reached, the clip 46' operates the lever 42' in a similar manner, and 45 shifts the worm 10' into driving engagement as shown in Fig. 2, thus reversing the travel of the ribbon.

The levers 42 and 42' have extensions 47 and 47' respectively attached thereto, and 50 connected by a light tension spring 48, which serves to return the frame 33 to its neutral or disengaged position, as soon as the shift has been accomplished and the ribbon begins to wind up, relieving the pressure of the ribbon clips 46 or 46' against the slot 45 or 45'. This keeps the hooks 36 and 36' normally out 55 of line with the projections 40 and 40', so that they will not continually be struck by the swing of the bail 19.

In order to hold the shaft 11 in position 60 after it has been shifted as described, it passes at its ends thru bearings 50 and 50', which are of the yieldable detent type, as shown more particularly in Fig. 4, Fig. 5, Fig. 6, and Fig. 65 7, as well as Fig. 1 and Fig. 2. This bearing

50 is made of two parts 51 and 52 as shown in Fig. 5, held together by the spring 53. The bearing parts 51 and 52 are relatively thin, so as to permit the shaft 11 to run in either of two non-parallel positions without 70 binding. The part 51 is fixed to the supporting bracket 6, while the part 52 is pivoted at 54, and is provided with two recesses 55 and 56, with a tongue or detent projection 57 separating them. When the shaft 11 is in one position it fits in the recess 56, and when the shaft 11 is shifted to the other position, as described, it fits in the recess 55. When it shifts from one position to the other, the pressure of the shaft 11 on the tongue 57 raises 80 the bearing cap 52 against the force of the spring 53 and permits the shift. After the shift has been made, the tongue 57 under the tension of the spring 53 is in general sufficient to hold the shaft 11 from displacement. 85

In changing ribbons it is desirable that both spools be permitted to turn freely, so that the operator, by spinning one of the spools by hand, may be able to rapidly wind the ribbon all on one spool. One mechanism 90 for permitting this free winding has been described, namely, the spokes of the wheels 9 or 9' being arranged to freely over-ride on the inclined faces of the cams 3'. This allows the spool whose worm wheel is locked 95 by the worm to be wound up freely by hand (though it cannot be turned by hand in the opposite direction), while the other spool, whose worm wheel is not engaged with its worm, is of course free to spin in either direction, and so can unwind its ribbon on to the winding spool.

My construction also permits another method whereby both spools are released for 105 free winding, if desired. The cross-shaft 11 projects slightly from each side of the machine, so that it can be reached by the operator's finger, and if this shaft 11 is moved by hand to a position midway between its two normal positions, both of the worms 10 and 110 10' will be out of contact with their respective worm wheels 9 and 9', so that both worm wheels will be free to spin. When the shaft 11 is in this mid-position, it will be under the detent tooth 57 of Fig. 4 and Fig. 5. While 115 the detent will have a tendency to move the shift into one or the other of its normal positions, the shaft is easily held by the hand. This construction also permits a hand reverse when desired, as the operator by the 120 touch of a finger can throw the shaft 11 into the other detent notch and so reverse the ribbon.

In the foregoing I have explained and 125 described a preferred form of my invention in certain specific examples, but it will be understood that these are only by way of illustration, and that the apparatus is susceptible of various modifications and adaptations as will be apparent to those skilled in the art, 130

without departing from the scope of the invention, which is specified in the following claims.

I claim:

- 5 1. In a ribbon feed mechanism, the combination of a number of key operated driving members, a bail adapted to be operated by any one of said members, a ratchet wheel, and a pawl pivoted to said bail and adapted 10 to drive the ratchet wheel, the pivot of the pawl and the pivotal axis of the bail being substantially in the line of action of the pawl at the beginning of a driving stroke, whereby the starting shock is reduced. 15 2. In a ribbon feed mechanism, the combination of a cross-shaft mounted for rotation on its own axis and for oscillation about a transverse axis intermediate its ends, spool driving gears on opposite sides of the axis 20 of oscillation, corresponding gears on the cross-shaft arranged to drive the spool gears in opposite directions and adapted to be brought alternately into driving engagement by oscillation of the cross-shaft, a supporting 25 bearing for said shaft having two sockets and a yieldable detent projection between them, said bearing being proportioned so that said shaft may shift from one socket to a non-parallel position in the other socket. 30 3. In a ribbon feed mechanism the combination of a spool shaft, a gear loosely mounted on said shaft for both rotary and axial motion, and a tooth mounted on said shaft and adapted to engage the gear, said tooth having 35 a driving face and an overrunning face, whereby in one direction of rotation the gear will drive the shaft, and in the other direction of rotation the gear will over-ride the tooth and permit the shaft to turn freely. 40 4. In a ribbon feed mechanism, the combination of a spool shaft, a worm wheel loosely mounted on said shaft for both rotary and axial motion, a worm adapted to mesh with 45 said worm wheel, and a tooth mounted on said shaft and adapted to engage the gear, said tooth having a driving face and an over-running face, whereby in one direction of rotation the gear will drive the shaft, and in the other direction of rotation the gear will 50 over-ride the tooth and permit the shaft to turn freely. 5. In a ribbon feed mechanism, the combination of a spool shaft, a gear loosely mounted on said shaft for both rotary and axial motion, said gear having a plurality of spokes, and a plurality of teeth mounted on said shaft and adapted to engage the spokes, the 55 number of spokes differing from the number of teeth so as to reduce the angular travel necessary for engagement, said teeth having driving faces and over-running faces, whereby in one direction of rotation the gear will 60 drive the shaft, and in the other direction of rotation the gear will over-ride the teeth and 65 permit the shaft to turn freely. 6. In a ribbon feed mechanism, the combination of a spool shaft, a worm wheel loosely mounted on said shaft for both rotary and axial motion, said gear having a plurality of spokes, a worm adapted to mesh with said worm wheel, and a plurality of teeth mounted on said shaft and adapted to engage the spokes the number of spokes differing from the number of teeth so as to reduce the angular travel necessary for engagement, said teeth having driving faces and over-running faces, whereby in one direction of rotation the gear will drive the shaft, and in the other direction of rotation the gear will over-ride the teeth and permit the shaft to turn freely. 7. In a ribbon feed mechanism the combination of driving members, a movable member which is oscillated by the stroke of the driving members, a pair of spool driving gearings, arranged for opposite directions of 85 rotation, a frame connected to said gearings and arranged so that when one gearing is in driving engagement the other gearing is out of engagement, cooperating means between said movable member and said frame whereby the frame may be shifted on the single oscillation of the movable member, means for bringing said cooperating means into operative position, and means for withdrawing the cooperating means from operative position after reversal of the ribbon. 90 8. In a ribbon feed mechanism, the combination of a reversing frame mounted to swing about a pivot, a cross-shaft journalled in said frame, a shifting frame having bearings for said shaft relative to which the cross-shaft may both rotate for driving and move longitudinally for shifting, means for moving said shifting frame longitudinally on the cross-shaft, and actuating means 100 adapted to engage the shifting frame at either one of two points, whereby the shifting frame, shaft, and reversing frame may be swung about the pivot, and a ribbon feed mechanism arranged to be reversed thereby. 105 9. In a ribbon feed mechanism, the combination of a reversing frame mounted to swing about a pivot, a cross-shaft journalled in said frame, a shifting frame having bearings for said shaft relative to which the cross-shaft may both rotate for driving and move longitudinally for shifting, means for moving said shifting frame longitudinally on the cross-shaft, a pair of engaging means on said shifting frame capable of yielding in the line of shifting, actuating means adapted to engage one or the other of said engaging means and move them transversely to the line of shifting, whereby the shifting frame, shaft, and reversing frame may be swung about the pivot, and a ribbon feed mechanism arranged 115 to be reversed thereby. 120 10. In a ribbon feed mechanism, the combination of a reversing frame mounted to swing about a pivot, a cross-shaft jour- 125

- nalled in said frame, a shifting frame having 5
bearings for said shaft relative to which the
cross-shaft may both rotate for driving and
move longitudinally for shifting, means for
moving said shifting frame longitudinally on
the cross-shaft, means for restoring the shift-
ing frame to a neutral position, and actuati-
ng means adapted to engage the shifting frame
at either one of two points, whereby
10 the shifting frame, shaft, and reversing
frame may be swung about the pivot, and a
ribbon feed mechanism arranged to be re-
versed thereby.
11. In a ribbon feed mechanism, the
15 combination of a reversing frame mounted
to swing about a pivot, a cross-shaft jour-
nalled in said frame, a shifting frame hav-
ing bearings for said shaft relative to which
the cross-shaft may both rotate for driving
20 and move longitudinally for shifting, means
for moving said shifting frame longitudi-
nally on the cross-shaft, means for restoring
the shifting frame to a neutral position, a
pair of engaging means on said shifting
25 frame capable of yielding in the line of shift-
ing, actuating means adapted to engage one
or the other of said engaging means and
move them transversely to the line of shift-
ing, whereby the shifting frame, shaft, and
30 reversing frame may be swung about the
pivot, and a ribbon feed mechanism arranged
to be reversed thereby.
12. In a ribbon feed mechanism, the com-
bination of a pair of ribbon spools, a ribbon
35 arranged to wind and unwind between them,
clips near the ends of the ribbon, slotted levers
adapted to be moved by said clips, a shifting
frame movable by said levers, bearings car-
ried by said shifting frame, a shaft
40 mounted in said bearings for both rotary
and axial relative motion, a second frame
pivoted intermediate the two spools, bear-
ings for said shaft on said second frame,
whereby the shifting frame, second frame,
45 and shaft are interconnected for oscillatory
motion about the pivot of the second frame,
over-running clutch devices connected to
drive said spools in opposite directions al-
ternatively, gear wheels adapted to rotate the
50 clutch devices, two driving gears mounted on
said shaft and adapted to drive the gear
wheels alternatively in opposite directions, a
ratchet wheel mounted on said shaft inter-
mediate the two driving gears, a ratchet
55 drive mechanism for said ratchet, a pair
of spaced engaging points on said shifting
frame, a pair of differently spaced engaging
elements having an oscillatory motion,
whereby one or the other of said points on
60 said shifting frame may be engaged when the
frame is shifted, and the shaft swung about
the pivot to engage one driving gear and
disengage the other.
13. In a ribbon feed mechanism, the com-
65 bination of a pair of ribbon spools, a ribbon
arranged to wind and unwind between them,
clips near the ends of the ribbon, slotted levers
adapted to be moved by said clips, a shifting
frame movable by said levers, bearings car-
ried by said shifting frame, a shaft mounted
70 in said bearings for both rotary and axial
relative motion, a second frame pivoted in-
termediate the two spools, bearings for said
shaft on said second frame, whereby the shift-
ing frame, second frame, and shaft are inter-
75 connected for oscillatory motion about the
pivot of the second frame, means to steady
said shaft in one or the other of its shifted
positions, over-running clutch devices con-
nected to drive said spools in opposite direc-
80 tions alternatively, gear wheels adapted to
rotate the clutch devices, two driving gears
mounted on said shaft and adapted to drive
the gear wheels alternatively in opposite di-
rections, a ratchet wheel mounted on said
85 shaft intermediate the two driving gears, a
ratchet drive mechanism for said ratchet, a
pair of spaced engaging points on said shift-
ing frame, a pair of differently spaced engag-
ing elements having an oscillatory motion,
90 whereby one or the other of said points on
said shifting frame may be engaged when the
frame is shifted, and the shaft swung about
the pivot to engage one driving gear and dis-
engage the other.
14. In a ribbon feed mechanism, the combi-
nation of a pair of ribbon spools, a ribbon ar-
ranged to wind and unwind between them,
clips near the ends of the ribbon, slotted levers
adapted to be moved by said clips, a shifting
100 frame movable by said levers, means for re-
storing said shifting frame to a neutral posi-
tion, bearings carried by said shifting frame,
a shaft mounted in said bearings for both
rotary and axial relative motion, a second
105 frame pivoted intermediate the two spools,
bearings for said shaft on said second frame,
whereby the shifting frame, second frame,
and shaft are interconnected for oscillatory
motion about the pivot of the second frame,
110 over-running clutch devices connected to
drive said spools in opposite directions al-
ternatively, gear wheels adapted to rotate the
clutch devices, two driving gears mounted on
said shaft and adapted to drive the gear
115 wheels alternatively in opposite directions, a
ratchet wheel mounted on said shaft inter-
mediate the two driving gears, a ratchet drive
mechanism for said ratchet, a pair of spaced
engaging points on said shifting frame, a pair
120 of differently spaced engaging elements hav-
ing an oscillatory motion, whereby one or the
other of said points on said shifting frame
may be engaged when the frame is shifted,
and the shaft swung about the pivot to engage
125 one driving gear and disengage the other.
15. In a ribbon feed mechanism, the combi-
nation of a pair of ribbon spools, a ribbon ar-
ranged to wind and unwind between them,
clips near the ends of the ribbon, slotted levers
130

- adapted to be moved by said clips, a shifting frame movable by said levers, bearings carried by said shifting frame, a shaft mounted in said bearings for both rotary and axial 5 relative motion, a second frame pivoted intermediate the two spools, bearings for said shaft on said second frame, whereby the shifting frame, second frame, and shaft are interconnected for oscillatory motion about 10 the pivot of the second frame, over-running clutch devices connected to drive said spools in opposite directions alternatively, gear wheels adapted to rotate the clutch devices, two driving gears mounted on said shaft and 15 adapted to drive the gear wheels alternatively in opposite directions, a ratchet wheel mounted on said shaft intermediate the two driving gears, a ratchet drive mechanism for said ratchet, a pair of spaced engaging points on 20 said shifting frame, a pair of differently spaced engaging elements having an oscillatory motion, whereby one or the other of said points on said shifting frame may be engaged when the frame is shifted, and the shaft 25 swung about the pivot to engage one driving gear and disengage the other, and yieldable means to limit the friction of said engaging points and engaging elements when the shifting frame is being moved into operative engagement. 30
16. In a ribbon feed mechanism, the combination of a pair of ribbon spools, a ribbon arranged to wind and unwind between them, clips near the ends of the ribbon, slotted
- levers adapted to be moved by said clips, a shifting frame movable by said levers, means for restoring said shifting frame to a neutral position, bearings carried by said shifting frame, a shaft mounted in said bearings for both rotary and axial relative motion, a second frame pivoted intermediate the two spools, bearings for said shaft on said second frame, whereby the shifting frame, second frame, and shaft are interconnected for oscillatory motion about the pivot of the second frame, means to steady said shaft in one or the other of its shifted positions, over-running clutch devices connected to drive said spools in opposite directions alternatively, gear wheels adapted to rotate the clutch devices, two driving gears mounted on said shaft and adapted to drive the gear wheels alternatively in opposite directions, a ratchet wheel mounted on said shaft intermediate the two driving gears, a ratchet drive mechanism for said ratchet, a pair of spaced engaging points on said shifting frame, a pair of differently spaced engaging elements having an oscillatory motion, whereby one or the other of said points on said shifting frame may be engaged when the frame is shifted, and the shaft swung about the pivot to engage one driving gear and disengage the other. 65
- In testimony whereof, I have hereunto signed my name this sixth day of May, 1927.

JOHN H. BARR.
